UNITED STATES PATENT OFFICE.

GIDEON C. BATTEN, OF CINCINNATI, OHIO, ASSIGNOR TO INTERNATIONAL MOLDING MACHINE COMPANY, OF CHICAGO, ILLINOIS, A CORPORATION OF ILLINOIS.

MOLDING-MACHINE CLAMPING MECHANISM.

1,167,877.

Specification of Letters Patent. Patented Jan. 11, 1916.

Application filed April 20, 1915. Serial No. 22,706.

To all whom it may concern:

Be it known that I, GIDEON C. BATTEN, a citizen of the United States, residing at Cincinnati, in the county of Hamilton and State of Ohio, have invented certain new and useful Improvements in Molding-Machine Clamping Mechanism, of which the following is a specification.

My invention relates to improvements in locking mechanism for molding machines.

One of its objects is to provide simple, efficient, reliable and practical means to lock the flask section to the molding machine platen while it is being reversed and transferred from the forming or ramming plunger or standard to the receiving or supporting standard.

Another object is to provide locking means which may be conveniently and quickly applied and released, and is not in the way or liable to disturb the flask member in being applied or detached therefrom.

My invention also comprises certain details of form, combination and arrangement, all of which will be fully set forth in the description of the accompanying drawings in which—

Figure 1. is a side elevation partly in section of a molding machine with the flask member on its ramming standard ready to be reversed and transferred. Fig. 2. is a similar view after the flask member has been transferred and reversed. Fig. 3. is a perspective view of the hinged locking member detached. Fig. 4. is a similar view illustrating a modification. Fig. 5. is a perspective view of the detachable locking member detached. Fig. 6. is a bottom plan view of the spring latch member. Fig. 7. is a perspective view of the latch releasing cam member detached. Fig. 8. is a detail in side elevation illustrating a modification of the latch mechanism.

The accompanying drawings illustrate the preferred embodiment of my invention in which—

A represents the base of a general type molding machine.

B represents a standard on which the mold board D is supported and jarred or vibrated to cause the molding sand to settle firmly about the pattern which is attached to or rests upon the mold board. A flask

member E, either the cope or drag, is seated upon the mold board and held in position 55 relative thereto by means of dowel pins not shown. As soon as the flask member has become filled with sand the upper surface of the sand is leveled off and a bottom board or platen F is placed over the sand upon the 60 flask member E and the parts are ready to be locked together in order that the flask member E and bottom board F containing the molded sand may be turned up side down 65 and transferred to the supporting standard H, and the mold board and pattern detached therefrom and returned to the standard B ready to receive another flask member to form another sand mold.

K represents a frame pivotally supported 70 upon a center 2, on the standard L, the frame K has forked arms k to pass on opposite sides of the standard B and to which the mold board D is attached. A cylinder 3 and plunger f serve to move the frame K 75 through substantially a half circle about the center 2 from the position Fig. 1 to the position Fig. 2, and return. In order to firmly lock the flask member E the platen F and the contained sand to the mold board 80 D and frame K while being moved from standard B to standard H, I provide a member 4 hinged at 5 to the arms k of frame K with its shank freely movable and provided with a series of perforations 6. A metal 85 bar 7 has a shank 8 to enter any desired one of the holes 6. A shoe 7' is preferably attached by a bolt to the bar 7 and interposed between the bar 7 and the bottom board F in order to apply pressure centrally 90 and evenly to the bottom board, for which purpose the meeting faces of the shoe and bar 7 have a substantially ball and socket adjustment relative to each other. Hinged to the opposite end of the bar 7 is a toothed 95 bar 10 the serrated end of which enters a recess 11 between the stationary latch member 12 and the spring actuated latch member 14. The latch member 12 is fastened to the mold board D or arms k of frame 100 K while the member 14 is mounted upon and guided relative to member 12 by the stud bolts 15, and held yieldingly in place to engage the serrated face of the bar 10 by means of springs 16, locked thereto by 105 nuts 17. A yoke shaped lever 18 is piv-

oted to member 12 at 19 and has cam faces to engage member 14 at opposite ends to force member 14 outwardly to release the bar 10 when desired.

5 In practice the depth of the flask members vary from time to time depending upon the shape of the pattern and the series of holes 6 enables one to be selected at substantially the right height above the bottom board F 10 into which to insert the shank 8. The tapered end of bar 10 is then inserted into the recess 11 and pressure applied where the bars 7 and 10 are hinged together to force bar 10 as far as possible into recess 11 15 whereupon the spring actuated member 14 engages the teeth of bar 10 and locks all the parts in position ready to reverse the flask section. After the flask section has been reversed in position and transferred to the 20 standard H the bottom board F rests in a horizontal position upon four projections 20 and the bar 7 occupies a position between said projections free to be removed. The latch member 14 is released by means of the 25 levers 18 and the bars 7 and 10 detached. Then the frame K and mold board D with the pattern are detached from the sand and flask member E and returned to the position Fig. 1. During this return movement the 30 locking member 4 swings freely upon its center 5 so as not to contact with and upset, jar, or injure the parts resting upon the standard H. Where unusually deep flask members are to be employed I preferably 35 employ a locking member 4' see Fig. 4, having centers 5' to hinge it to a frame K and a hinged joint 30 to enable the member 4' to return to its original position without liability of contacting with the flask member 40 supported upon the standard H. For unusually heavy flasks I preferably employ as illustrated in Fig. 8 a bar 10' having a rack 31 which is engaged by a pinion 32 journaled to a frame 33 attached to the mold 45 board D. A hand crank 34 serves to turn the pinion to draw the bar 10' into locked position and a pawl 35 engages the pinion to hold the parts in locked position.

The mechanism herein illustrated and 50 scribed is capable of considerable modification without departing from the principle of my invention.

Having described my invention, what I claim is:

1. In combination with the mold board 55 and transposing frame of a molding machine, a locking mechanism comprising a locking member hinged to said frame and a latch member carried rigidly relative to said frame, and a detachable member composed of two bars hinged together and provided with means to detachably engage their free ends respectively with the free end of said hinged locking member and said latch member. 60

2. In combination with the mold board and transposing frame of a molding machine a locking mechanism comprising a horizontally disposed cross bar above a flask member to hold it in position upon the mold 70 board, a vertically disposed toothed bar hinged at one end to said cross-bar, and means carried by said frame to detachably engage the free ends of said respective bars. 75

3. In combination with the mold board and transposing frame of a molding machine, a locking mechanism comprising a locking member hinged at one end to said frame, and free at its opposite end, and located at one side of said mold board a latch 80 member carried by said frame at the opposite side of said mold board, a cross-bar detachably and adjustably connected to the free end of said hinged member, and a toothed bar hinged at one end to said cross-bar and detachably and adjustably engaged at its opposite end to said latch member. 85

4. In combination with the mold board and transposing frame of a molding machine a locking mechanism, comprising a 90 horizontally disposed cross-bar, a tiltable shoe carried by said bar to engage and lock a flask member and bottom board to said mold board, a vertically disposed bar hinged at one end to said cross bar, and means carried by said frame to detachably engage the free ends of said respective bars. 95

In testimony whereof I have affixed my signature in presence of two witnesses.

GIDEON C. BATTEEN.
